WIRE BARBING MACHINE.

No. 361,928.

Patented Apr. 26, 1887.

UNITED STATES PATENT OFFICE.

HENRY A. CLOW, OF DES MOINES, IOWA.

WIRE-BARBING MACHINE.

SPECIFICATION forming part of Letters Patent No. 361,928, dated April 26, 1887.

Application filed January 10, 1885. Serial No. 152,454. (No model.)

To all whom it may concern:

Be it known that I, HENRY A. CLOW, a citizen of the United States, residing at Des Moines, in the county of Polk and State of Iowa, have 5 invented a new and useful Improvement in Wire-Barbing Machines, of which the following is a specification.

This invention relates to wire-barbing machines; and it consists in certain novel features of construction and combination, herein- 10 after fully described, and specifically pointed out in the claims.

The invention is illustrated by the accompanying drawings, in which—

15 Figure 1 is a plan view of my improved wire-barbing machine. Fig. 2 is a front elevation of the same, except shaft D' and its bearing d³ and a portion of the front legs of the machine, which several parts are removed in this 20 figure in order to more fully exhibit the barb-applying mechanism. Fig. 3 is an enlarged front view of that portion of the barb-applying mechanism shown in Fig. 2, but with the bed-plate A broken away on the dotted line 25 x x of Fig. 1. Fig. 4 is a front elevation showing that portion of the barb-applying mechanism which comes more immediately in contact with the barb when the same is being attached to the fence-wire. This figure also exhibits a 30 staple-barb in position, ready to be secured to the main fence-wire. Fig. 5 is a like view showing the barb secured to the main fence-wire and the barb-forming devices in the relative positions which they occupy at the instant

35 the barb has been completely attached to said main wire. Fig. 6 is a vertical longitudinal section of the upright standard C, showing only that portion, however, which is located immediately adjacent that part of the machine 40 where the barbs are applied to the main wire. Figs. 7, 8, and 9 illustrate the style of barb fence-wire manufactured on my machine. Fig. 10 is a side elevation of the staple-holder K. Fig. 11 is an end view of said holder, looking 45 from the right in Fig. 10.

The object of my invention is the construction of a barbing-machine adapted to apply staple-formed barbs to a fence-wire at regular intervals of space along said wire by automatically placing staple-barbs, one at a time, astride 50 the main fence-wire and holding them succes-

sively in that position, and pushing the pointed ends of the barb from the opposite sides of the main fence-wire past each other and across the main wire in such manner that the barb will 55 completely encircle the main wire and the points project from said main wire in opposite directions, or nearly so.

In Fig. 1, A is a bed-plate, to which is attached the operating mechanism. 60

B B are legs employed to support the bed-plate.

D is the main driving-shaft, mounted in bearings d d', suspended from the bed-plate.

a is a pulley rigidly secured to shaft D, and 65 receives the driving-belt.

D' is a shaft situated at right angles to shaft D, and is mounted in a bearing, d', secured to one of the legs B. This shaft is driven by miter-gears a' a². 70

D² is a cross-shaft parallel with shaft D, mounted in bearings d¹ d², which are attached to the front legs of the machine. On this shaft are secured a sprocket-wheel, b, and a pin-wheel, a⁴. Shaft D² is rotated intermittently 75 by a cam-wheel, a³, rigidly secured to shaft D', and arranged to engage the pins in pin-wheel a⁴ at each revolution of shaft D'. The pin-wheel and shaft D² are rotated through an arc corresponding to the pitch of the pin-wheel. 80 Sprocket-wheel b is employed to advance the main fence-wire through the machine at regular intervals as the barbs are applied and to regulate the spaces between the barbs on said main wire. 85

C C' C² is a standard secured to the top of the bed-plate, that portion, C', which extends upward being provided with a groove in its front face, in which groove the barb pusher and holder e⁶ is held in position and operated, as 90 hereinafter described. Those portions of the standard C and C² which extend laterally along the bed-plate are constructed with grooves in the front face for the reception of the barb-benders e and e². 95

e' and e⁴ are cams mounted on shaft D directly beneath the barb-pushers, above referred to, e and e², and secured to said shaft by splines or feathers, which prevent the cams from rotating around the shaft, but permit 100 them to slide lengthwise of the shaft.

f and f' are collars rigidly secured to shaft

D, and limit the movement of the cams inward or toward the center of the machine.

g and g' are coil-springs, which abut against the outside of the cams e and e', and suitable compression is secured on the springs by the collars h and h', secured to shaft D. These coil-springs are employed to provide elasticity to the sliding barb-benders e and e', and thereby adapt the machine to operate upon the varying sizes of wire without otherwise changing the adjustment and regulating the movement of the benders to each particular size of wire.

The barb pushers or benders e and e' are operated by the cams e' and e through the studs and rollers 1 2 and 3 4, as shown in Fig. 2. These studs are rigidly secured to the barb-benders e and e', and extend through openings 5 and 6 in the bed-plate.

I² is a standard slotted at the top, rising from 20 and secured to the bed-plate.

I⁴ is a lever pivoted at one end in the slot above referred to, and having its opposite end thrust through an opening in the vertical barb-holder e⁶, as shown at I⁴, Fig. 2.

I⁸ is a slotted standard suspended from the under side of the bed-plate.

I' is a lever having one end pivoted in the slot of said standard I⁸, and having the other end connected to the bed-plate by a spring, I⁵.

I³ is a link, which extends from the lever I' through an opening in the bed-plate to the lever I', and is pivoted to each of said levers.

I is a cam-wheel rigidly secured to shaft D, and immediately over lever I'. Cam I and spring I⁶ are employed to operate the barb-pusher e⁶, the downward movement of said pusher being secured by the pressure of the cam upon lever I', and the upward movement by the spring I⁶, when the cam has been rotated 40 so as to relieve the lever from pressure.

W' is a guide for the main fence-wire.

k is a standard rising from the bed-plate and secured thereto, and forms the support for a staple-barb holder, K. This staple-holder is 45 arranged at an angle to the direction of the passage of the main fence-wire as the latter passes from the guide W' through the barbing device to the sprocket-wheel b, and is inclined downward toward the barb-holder e⁶, so that the staples-barbs when placed thereon will, by their gravity and the jar of the machine when in operation, slide down against the holder e⁶; and when the holder is raised to sufficient height to permit will slide one at a time under the 55 lower end of said pusher, and will rest against the face of the back of the groove in the standard C', as shown in Figs. 3 and 6. Barb-holder K is provided with a slot in the end nearest the standard C', which is shown in Figs. 10 and 11. In this slot is pivoted a subordinate holder, K', the pivot being at K".

y is a spring secured to the bottom of holder K, and extends up into the slot and in rear of the subordinate holder K', as indicated by dotted lines in Fig. 10. This subordinate holder is arranged to support the staple-barbs one at a time as they drop down under the lower end

of the barb-pusher e⁶, and to prevent more than one such barb from dropping off the holder K during each upward and downward stroke of 70 the barb-pusher e⁶.

The barb-benders e and e' are constructed with fingers 7 and 8, adapted to catch the prongs of the barb whether it has been bent into a perfect staple or not, and shoulders 9 75 and 10, which press the barb hard against the main wire at the moment the barb is attached to the main fence-wire. Barb-bender e' is also provided with a thin extension, e³, which projects beyond the end of the finger 8 80 and lies adjacent to the other barb-bender, e. The object of this extension is to keep the points of the staple-bars separate from each other, and to prevent them from impinging upon each other while they are being pushed 85 in opposite directions past each other in the act of attaching the barb to the main wire.

It will be observed that the groove in standard C', in which the barb-pusher e⁶ operates, is inclined at an angle to the barb-benders e and e' and to the main fence-wire, and that the barb-support K is arranged at a right angle to the face of said groove. This arrangement allows the staple-barb, when pushed down by the barb-pusher e⁶, to come astride the main 95 fence-wire W, with one point or prong on the rear of the extension e³ and the other point in front of said extension, as shown in Fig. 4.

S S are guides to direct the staple-bars in their downward passage from the barb-support K' to the main wire.

No device is shown for reeling up the barbed wire, no claim being made to any such device, and any well-known method of winding up being applicable to this machine.

From the description given in detail of the function of the several parts of my machine the operation of the entire machine will be perfectly plain.

Having now fully described my invention, 110 what I claim as new, and desire to secure by Letters Patent, is—

1. The driving-shaft D, having cams e' e⁴, in combination with the sliding barb-benders e and e', having studs 1 and 2, substantially 115 as and for the purpose set forth.

2. Lever I', link I³, lever I⁴, barb-pusher e⁶, spring I⁵, and cam I, with means for operating said cam, substantially as described, and for the purpose set forth.

3. Lever I', link I³, lever I⁴, barb-pusher e⁶, spring I⁵, and cam I, with means for operating said cam, in combination with the barb-support K, substantially as described, and for the purpose set forth.

4. The barb-support K, having the subordinate support K' and spring y, in combination with standard C' and barb pusher and holder e⁶, substantially as described, and for the purpose set forth.

5. The barb-pusher e⁶, operated by cam I, in combination with barb-benders e and e', operated by cams e' and e⁴, and mechanism connecting said pusher and benders with their

operating-cams, all the cams being mounted on one shaft, D, substantially as described, and for the purpose set forth.

6. The barb-bender e^2 , having the extension 5 e^3 , in combination with barb-bender e , the grooved standard C', placed at an angle to said benders, and means to operate each of said benders, substantially as described.

7. A driving-shaft having cams, in combination with sliding barb-benders having studs 10 operated by said cams, by means of which the barb-benders are actuated to bend barb-prongs

in opposite directions about a main wire, substantially as described.

8. The collars f and f' , springs g and g' , collars h and h' , all mounted upon one shaft, with cams e^4 and e^5 , in combination with barb-benders e and e^2 , having studs 1 and 2, substantially as described, and for the purpose set forth. 15
